UNITED STATES PATENT OFFICE.

EDWARD G. FINZER, OF SUGAR CREEK, OHIO.

PORTABLE KILN-STACK BLOWER.

Application filed December 6, 1927. Serial No. 238,095.

My invention relates to portable blowers, for use in increasing the draft through the furnaces and the interior of a kiln, more particularly of the down draft type, during the 5 heating of the kiln towards the desired maximum burning temperature.

As usually constructed a kiln of the down draft type for burning brick or other clay products includes a cylindrical side wall, a 10 crown covering the upper end of the wall, a kiln bottom, and a checkered floor spaced above the bottom. A series of fire boxes are located around the side wall, and each communicates with the interior of the kiln, usually through an upwardly directed opening. The kiln bottom usually communicates 15 through a laterally extending duct with a vertical stack which may be laterally spaced some distance away from the kiln.

20 The products of combustion thus pass from the fire boxes into the kiln interior and about the clay products or ware which may be piled therein, down through the checkered floor, and out laterally through the duct to the kiln 25 stack.

In heating up kilns of the down draft type to the desired maximum burning temperature, it has been the usual practice to build 30 fires in the several fire boxes, and to utilize only whatever natural draft may be pulling through the same and out the cool lateral duct and up the cool stack.

This natural draft, when the fires are started is relatively slight, does not support efficient 35 combustion, tends to heat the crown first, and to soot, the kiln interior and the clay ware therein. Accordingly, four or more days may be required to heat the kiln, the cold and damp clay ware stacked therein, 40 the duct, and the stack walls to their respective necessary temperatures, and to bring the kiln interior and the clay ware therein to the desired maximum burning temperature.

Moreover, while in a usual clay products 45 plant, one stack may be utilized for several kilns, in large plants having many kilns there may be a great many stacks, very few if any of which are in operation for heating up their respective kilns at the same time.

50 Accordingly, the objects of the present improvements include the provision of portable means adapted for use successively as required in the various kiln stacks in a clay products plant for increasing the draft 55 through the furnaces of the kiln, the kiln interior, the lateral communicating duct, and

the stack therefor, during the period when the kiln is being heated up towards the desired maximum burning temperature; whereby efficient combustion in the furnaces is attained, 60 the kiln floor and clay ware thereon, and the kiln bottom are heated up at substantially the same rate as the side wall and crown, thereby avoiding sooting; and whereby the duct and stack walls are rapidly brought to their proper temperatures; thereby decreasing the total required burning time, and consequently increasing the yearly productive capacity of each kiln, reducing the quantity of fuel necessary, and providing consequent savings in 70 labor, material, and capital investment.

These and ancillary objects are attained by a construction and arrangement hereinafter set forth in detail, and which may be stated in general terms as including a longitudinally 75 extending frame, brackets extending laterally intermediate the ends thereof and adopted for removable association with a carriage for transporting the kiln draft blower from one kiln to another, a motor mounted at one 80 end of the frame, a fan preferably of the airplane propeller type mounted at the other end of the frame, a driving connection between the fan and the motor, the frame being adapted for hanging through a damper opening in a kiln duct so that the propeller may induce a relatively high draft through the furnaces, the kiln, the duct and the stack, and move a relatively large volume of air and 85 products of combustion for a desired and relatively short period of time to bring the kiln interior and its contents towards the maximum burning temperature; the driving motor for the propeller being at the upper end of the frame outside of the duct so that the motor is protected from the excessive heat of the gases flowing through the duct and will 90 not obstruct the flow thereof.

A preferred embodiment of the improvements is illustrated in the accompanying 100 drawings forming part hereof, in which

Figure 1 is a side elevation of the improved portable kiln blower as arranged on its carriage ready for transporting to a kiln for use;

Fig. 2, a fragmentary vertical sectional view illustrating a down draft kiln and its associated duct and stack, together with the present improved stack blower arranged for use therewith;

Fig. 3, an enlarged view of the blower similar to Fig. 2, portions of the blower being illustrated in section; and

Fig. 4, a front elevation thereof as in the direction of the arrows 4—4, Fig. 3.

Similar numerals refer to similar parts throughout the several views.

5 The improved stack blower indicated generally at 10 includes a frame indicated generally at 11 which may comprise a pair of laterally spaced longitudinally extending angle members 12 and 12', one end 12^a and 12'^a respectively of each of which is laterally off-set providing laterally angled supports for a blower orifice plate 13 having a preferably circular blower orifice 14 therein. The outer end of the blower orifice plate may be 15 further reinforced by an angle member 15 laterally extending between the extremities of the ends 12^a and 12'^a of the angle members 12 and 12'.
A blower fan 16 preferably of the airplane 20 propeller type is mounted for rotation adjacent the orifice 14 preferably at the outer end of a blower stub shaft 17 provided with suitable anti-friction and thrust bearings 18 and 18' suitably mounted within an oil tight stub 25 shaft housing 19.

Angled braces 20 and 20' preferably extend between the outer end of the housing 19 and the laterally extending angle member 15 for supporting the housing 19 and its associated 30 and contained mechanisms.

A bevel gear 21 keyed upon the stub shaft 17 within the housing 19 is meshed with a bevel drive gear 22 secured at the outer end of a drive shaft 23 extending longitudinally 35 and parallel with the angle members 12 and 12' preferably within a tubular casing 24 from the stub shaft housing 19 at one end of the frame 11 to a flexible coupling 25 at the other end of the frame 11, which coupling 40 connects the drive shaft 23 with a suitable preferably electric motor 26 mounted upon the other ends 12^b and 12'^b of the angle members 12 and 12'.

A cable 27 connects the motor 26 with a suitable starting box 28 mounted at one side thereof, and which is connected with a suitable power line as by means of a cable 29. A handle 30 extends laterally between and connects the extremities of the ends 12^b and 12'^b 50 of the angle members 12 and 12'.

The drive shaft casing 24 is preferably supported by suitable longitudinally spaced struts 31 and 32 extending from and secured to the plate 13 and the angle members 12 and 55 12', respectively.

The end of the drive shaft 23 within the housing 19 is provided with a suitable anti-friction and thrust bearing 33, and adjacent the coupling 25 the other end of the shaft 23 60 is provided with a suitable anti-friction and thrust bearing 33' cooperating with the bearing 33; the cup of the bearing 33' being secured within a suitable enlarged head 34 for the tubular casing 24, suitable stuffing box 65 and bearing adjusting and locking nuts 35

and 35' being provided on suitable threads 36 on the shaft 23 adjacent the bearing 33'.

The inner end of the stub shaft bearing 18 reacts through the gear 21 against a suitable collar on the shaft 17, and the inner end of the bearing 18' reacts against an adjusting nut 37 screwed upon the shaft 17; and a lock nut 37' is provided to cooperate with nut 37 for securing the bearings 18 and 18' in desired positions of adjustment. 75

The stub shaft 17 extends outwardly through an aperture in a suitable stuffing box screw plug 38, which is screwed in a suitably threaded opening at one side of the housing 19, forms a stuffing box 39 for the shaft 17. 80

The stuffing box 39 is preferably packed with asbestos material for protecting the mechanism within the housing from the excessive heat incident to the use of the blower. The interior of the housing 19 preferably 85 contains a suitable lubricant 40.

Fig. 2 best illustrates the improved stack blower in use.

A kiln of the down draft type indicated generally at 44 includes a cylindrical side 90 wall 45, a crown 46 covering the upper end of the wall, a kiln bottom 47, and a checkered kiln floor 48 spaced above the bottom. Spaced fire boxes 49 are located around the side wall, and each communicates with the 95 interior of the kiln through an upwardly directed opening 50 at the upper end of the fire box bag wall 51 and the side wall 45.

The kiln bottom communicates through the laterally extending duct 52 with a vertically 100 extending kiln stack 53 laterally spaced from the kiln 44. Preferably at the foot of the kiln stack the duct 52 is provided with a damper opening 54 and a suitable damper plate 55 for covering the same. 105

An eye bolt 56 may be secured over the damper opening 54 in a suitable wall 57 of the stack 53; and the eye bolt may support a block and tackle 58, the lower hook end 59 of which secures the handle 30 of the improved blower; whereby a single workman may suspend the improved blower 10 so that the propeller 16, at the lower end of the frame in the position illustrated in Fig. 2, extends downwardly through the damper opening 54 110 into the duct 52, where the propeller is suitably located for providing a high draft for the kiln furnaces 49. The damper plate 55 may be provided with a suitable notch 60 for fitting around the shaft casing 24. 115

Accordingly, the motor 26 is located in the open air at the upper end of the frame 11, and can thus drive, without being submitted to the danger of overheating and burning up, the propeller 16 at the desired high speed in the duct 52 where the temperature constantly rises. 120

Just as soon as the fires are started in the furnaces 49, the motor is started to drive the propeller 16 located in the duct 52, whereby 125 130

a relatively large volume of air is drawn through the furnaces, and the kiln interior, and over the clay ware contained therein, through the checkered floor 48, the duct 52 and into the stack 53, raising with relatively great rapidity the temperature of the kiln walls and the clay ware contained in the kiln interior.

The propeller 16 is permitted to thus increase the kiln draft for about sixteen to eighteen hours in one kiln with which the improved blower has been used, after which time the temperature of the kiln interior has reached very nearly the maximum burning temperature.

The propeller 16 is then removed from the duct 52 by raising the blower frame by means of the block and tackle 58, after which the natural draft provided by the heated walls 20 of the duct 52 and the stack 53 is sufficient to finish the burning operation.

After the blower has been removed from the duct 52, as aforesaid, it may be supported upon a suitable carriage 62 as by means of 25 suitable U bearings 63 and 63' removably fitting over the carriage axle 64; the U bearings 63 and 63' being carried at the outer ends of V brackets 65 and 65', respectively, mounted upon and outwardly extending from the 30 angle members 12 and 12', respectively, at a suitable location intermediate their ends for balancing the blower on the carriage. The blower thus mounted and balanced on the carriage 62 may be moved to another kiln 35 stack for increasing the draft thereof as aforesaid.

Means for maintaining the blower in position in the duct 52 may include a bar 66 secured at its ends upon the brackets 65 and 40 65' and mounting at one side a nut 67 in which a jack screw 68 is screwed and adapted to be rotated by a sliding handle 69 passing through a suitable aperture therein.

The jack screw 68 is provided at its outer 45 end with a swivel plate 70 adapted to abut against the vertical man hole wall 71, so that the jack screw 68 may be turned to push the angle members 12 and 12' against the outer surface of the stack wall 57 thereby 50 maintaining the blower in the desired position for operation.

In one kiln with which the present improved stack blower has been used as aforesaid, the total burning time has been reduced 55 from 5-8 days to 3-5 days, which is a striking example of the economies effected by the improved blower.

I claim:

1. In combination, a duct for conveying hot gasses, one of the duct side walls having 60 a damper opening therein, and a unitary portable blower located in the duct, the blower including a frame extending longitudinally through the damper opening, one end of the frame being located within the 65 duct, and the other end of the frame being located outside the duct, and means maintaining the one end of the frame within the duct.

2. In combination, a duct for conveying hot 70 gases, one of the duct side walls having a damper opening therein, and a unitary portable blower located in the duct, the blower including a frame extending longitudinally 75 through the damper opening, one end of the frame being located within the duct, and the other end of the frame being located outside the duct, means maintaining the one end of the frame within the duct, and a rotary fan on the frame within the duct, the axis of rotation of the fan being angular to the longitudinally extending frame.

3. A unitary portable blower including a longitudinally extending frame, a fan operatively mounted at one end of the frame, the 85 axis of rotation of the fan being angular to the longitudinal axis of the longitudinally extending frame, motor means mounted at the other end of the frame, a driving connection between the motor and the fan, and 90 means for removably maintaining the fan end of the frame within a kiln duct.

4. A unitary portable blower including a longitudinally extending frame, a fan operatively mounted at one end of the frame, 95 motor means on the frame for rotating the fan, a bracket extending laterally from the frame intermediate the ends thereof, and means on the bracket for removably positioning the frame in a kiln duct.

5. A unitary portable blower including a longitudinally extending frame, a fan operatively mounted at one end of the frame, motor means mounted at the other end of the frame, a driving connection between the 105 motor and the fan, and means mounted on the frame intermediate its ends, and adapted for removable connection with the sides of the damper opening of a kiln duct for removably supporting the fan within the duct.

In testimony that I claim the above, I have hereunto subscribed my name.

EDWARD G. FINZER.
